(57) **CLAIM**

The ornamental design for frame for neurological fixation device, as shown and described.

DESCRIPTION

FIG. 1 is a top, front, right view of frame for neurological fixation device showing my new design;

FIG. 2 is a bottom, left, rear perspective view thereof;

FIG. 3 is a right side view thereof;

FIG. 4 is a left side view thereof;

FIG. 5 is a front view thereof;

FIG. 6 is a top view thereof; and,

FIG. 7 is a bottom view thereof.

The portions of the drawings illustrated in broken lines are directed to the boundary of the design and form no part of the claimed design.

1 Claim, 4 Drawing Sheets
